ALCID A. MEYER, OF MINNEAPOLIS, MINNESOTA

FOUNDRY TOOL

Application filed April 25, 1929. Serial No. 358,096.

This invention relates to certain improvements in foundry tools; and the nature and objects of the invention will be readily recognized and understood by those skilled in the art in the light of the following explanation and detailed description of the accompanying drawings illustrating what I at present believe to be the preferred embodiments or mechanical expressions of which my invention is capable from among various other forms, embodiments, arrangements, combinations, and constructions within the spirit and scope thereof.

The main object of the present invention is to provide a combination tool, or a multiplicity of tools carried by and cooperatively combined on a single handle or holder, that may be conveniently carried in the pocket for the use of a foundryman in working with molds and forming castings therein.

A further object of the invention is to provide such a tool in which the tool handle or holder with the tools carried thereby in their inoperative positions, will form and be capable of use as a sprue plug for forming the sprue opening in a manner familiar and well understood in this art.

A further object of the invention is to provide such a combination tool and holder therefor, in which a number of tools are provided of utility in foundry work, and which combination tool is of small compact and readily handled size capable of being carried in the pocket of the foundryman available for use at any time when needed.

With the foregoing general objects and certain other objects and results in view which will be readily recognized from the following description, the invention consists in certain novel features in construction and in combination and arrangement of elements as will be more fully and particularly referred to and specified hereinafter.

Referring to the accompanying drawings in which similar reference characters refer to corresponding parts throughout the several figures thereof:

Fig. 1 is a view in side elevation of a combination tool of the invention, with the tools

in their folded or inoperative positions on the tool holder or handle.

Fig. 2 is a transverse section taken on the line 2-2 of Fig. 1.

Fig. 3 is a vertical longitudinal section 55 taken on the line 3-3 of Fig. 1.

Fig. 4 is a vertical longitudinal section taken on the line 4-4 of Fig. 3.

In the particular form of the invention disclosed herewith purely by way of example 60 and not of limitation, a foundry tool embodies and includes the body or tool handle forming carrier 10 having an axial passage 11 therethrough from end to end thereof and in the present example of square or rectangular cross section. This body or tool carrier 10 which carries and on which the several tools thereof are mounted, serves the purpose of a handle for each of the tools when they are being used, and as a case or container for the 70 tools when they are in their inoperative or withdrawn position.

The tool handle forming body 10 is formed and provided in the specific example hereof, with a series of three slots or grooves 10a, 10b and 10c, extending inwardly therealong from one end of the handle 10 to and terminating a distance inwardly therefrom adjacent the central or intermediate portion of the handle.

A flat spring 12 is mounted longitudinally 80 of and along the inner side of each of the grooves 10a, 10b, and 10c, respectively, and is fixed at its inner end and free at its outer end adjacent the outer ends of the grooves for flexing or laterally springing, by under-cutting the outer portions of the grooves below these springs 12, as will be clear by reference to Figs. 3 and 4 of the drawings in particular.

A small scoop 14 is mounted in the groove 10a by means of a pin 14a extended transversely through the arm of the scoop and which is secured in opposite walls of the groove, so that the scoop extends longitudinally along and fits over and against the adjacent side of the member 10 and is capable 90 of being swung on pin 14a outwardly to the position indicated in dotted lines by Fig. 3.

A hoe 15 is similarly mounted by pin 15a in the handle groove 10b and in its folded position extends longitudinally along and 100

against member 10 with the hoe proper fitting over the outer end of the handle. The hoe 15 can be swung outwardly to operative position extending longitudinally from the member 10, which forms a handle therefor, to the position as indicated by dotted lines in Fig. 3.

The handle groove 10c carries a venting rod 16 mounted on a pin 16a at the outer end 10 of the groove 10c, in the manner described with respect to the scoop 14. In inoperative position the rod 16 extends longitudinally along and against the handle 10, and is swingable outwardly on pins 16a to operative position extending longitudinally from the body portion 10 which forms a handle therefor.

In each instance the tools 14, 15, and 16 at their outer ends engage and bear upon the springs 12, respectively, which springs 20 maintain the tools in their folded or inoperative, and in their outwardly swung operative position.

A combined screw driver and draw pin 17 having its body portion square or rectangular in cross section, is slidably mounted and confined in the longitudinal or axial bore 11 of the handle member 10. This combined screw driver and draw pin 17 has one end 17a formed to provide the screw driver and 25 the opposite end 17b formed to provide the draw pin. The combined tool 17 is confined in and adjustably positioned by means of a sliding pin 18 which extends transversely through the handle member 10 and the bore or 30 passage 11, at a point intermediate its ends. The pin 18 is slidably mounted in position in the handle 10 and is formed at one end with a head 18a accessible from the exterior of the handle in a recess 18b formed therein and normally covered by the shank of the hoe 15 which extends thereacross (see Figs. 2 and 3). The pin 18 is slidably confined in the handle 10 extending across the passage 11, by means 35 of a fixed retaining pin 19 disposed through one side of the body 10 and slidably engaged at its inner end in a groove 19a which extends longitudinally of the pin 18. At its inner end opposite the head 18a, the pin 18 is formed with a circumferential groove 19b 40 theretround for receiving and engaging the retaining pin 19 to prevent complete withdrawal and displacement of the pin 18 from the handle 10.

The combined screw driver and draw pin 55 18 is provided with a series of transverse bores 17c, 17d, and 17e, the bore 17c being located adjacent the screw driver end 17a, the bore 17e adjacent the draw pin end 17b, and the bore 17d being disposed intermediate the aforesaid bores. These bores 17c, 17d and 17e are adapted for selective registration with the sliding pin 18 in order to position the tool 17 in its inoperative position, its position functioning as a screw driver, or its 60 positioning functioning as a draw pin. For

example, in Fig. 3 the tool 17 is shown in position with the end 17b thereof extended from the handle 10 and the pin 18 extending through bore 17c of the tool to hold the same in its extended position to provide the draw pin 17b with the body portion 10 providing an operating handle therefor. The tool 17 in its inoperative position is withdrawn into the handle 10 until the intermediate bore 17d registers with pin 18, which pin extends therethrough and releasably secures the tool in its inoperative position. To function as a screw driver, the tool 17 is extended from the opposite end of handle 10 with the pin 18 registered with and extending through bore 17e. The pin 18 is operated to withdraw the same from the bores of tool 17, by swinging the hoe 15 outwardly from across recess 18b in the handle, whereupon the head 18a of the pin is grasped and the pin slid or withdrawn 80 outwardly from position across passage 11. The tool 17 is then moved through passage 11 until the desired bore of this tool is in registry with the pin, which is then pushed inwardly through the bore and holding the 90 tool in the desired adjusted position.

The combination implement or tool as above described, with the combination screw driver and draw pin in its inoperative position withdrawn into handle passage 11, and with the scoop 14, hoe 15 and venting rod 16 in their inwardly folded and inoperative positions along and against the handle 10, as shown particularly in Figs. 1 and 2, then forms and provides a sprue plug for forming the sprue opening in the mold. This is accomplished by placing the small end of the handle downwardly against the "drag" or lower half of the mold and filling the "cope", the upper part of the flask with sand, tamping the sand down, and then withdrawing the handle 10, which thus leaves the desired opening.

The scoop 14 provides an efficient and useful tool or instrument for handling sand, as does the hoe or L-shaped tool 15, while the venting rod 16 provides an implement which can be pushed downwardly through the sand and against the pattern to form small passages for the release and discharge of gas resulting from the hot molten metal coming in contact with the wet sand. The draw pin 17b provides an implement by which the pattern can be drawn from the sand by driving pin 17b into the pattern and then carefully lifting the same from the mold.

In every instance the body portion 10 forms an operating handle for whichever of the tools 14, 15, 16, and 17 may be extended in operative position therefrom, the handle 10 also forms the case or container into and against which these tools may be positioned when out of use, so as to provide a compact combination tool presenting no objectionable projecting edges, and capable of being easily 130

carried in the pocket of a workman ready for instant use when needed.

It is evident that various other forms, arrangements, combinations and constructions might be resorted to without departing from the spirit and scope of my invention, and hence I do not wish to limit myself in all respects to the exact and specific disclosures hereof.

10 Desiring to protect my invention in the broadest manner legally possible,

What I claim is:

15 A foundry tool comprising a handle member having a bore therethrough extending from end to end thereof, a tool slidably mounted in said bore for projection outwardly therefrom at either end of said handle member, a pin slidably mounted transversely of said member and extending across said 20 bore intermediate the ends thereof, said pin formed with a head for withdrawing the pin from across the bore and for sliding the same inwardly across the bore, the handle member formed with a recess at one side thereof receiving the head of said pin, the tool slidably mounted in said bore formed with a series of spaced transverse bores therethrough for receiving said pin to hold the tool in its several positions respectively, a tool pivotally 25 mounted and disposed longitudinally of the handle member at one end thereof, the said tool swingable inwardly onto and against the handle member and swingable outwardly to position extending longitudinally from one 30 end thereof, and said tool in position against the handle member extending across said recess and the pin head positioned therein to form a guard therefor.

35 Signed at Minneapolis, Hennepin County, Minnesota, this 6 day of April, 1929.

ALCID A. MEYER.
